FIG. 8

FIG. 1 is a perspective view of a combined mixer and dispenser showing my new design;

FIG. 2 is a front elevation view thereof;

FIG. 3 is a side elevation view thereof;

FIG. 4 is a rear elevation view thereof;

FIG. 5 is a top plan view thereof;

FIG. 6 is a perspective view of a combined mixer and dispenser showing another form of my new design;

FIG. 7 is a front elevation view thereof;

FIG. 8 is a side elevation view thereof;

FIG. 9 is a rear elevation view thereof; and

FIG. 10 is a top plan view thereof.

This application is a continuation-in-part of my applications Ser. No. D. 9,475, filed Nov. 20, 1967, and Ser. No. D. 10,737, filed Feb. 23, 1968, both now abandoned.

The characteristic feature of the design resides in the particular configuration and arrangement of the top surfaces of the control portion and battery housing.

I claim:

The ornamental design for a combined mixer and dispenser, as shown and described.
